UNITED STATES PATENT OFFICE.

FRANK M. WILLIAMS, OF WILKES-BARRE, PENNSYLVANIA, ASSIGNOR TO WILLIAM BULLOCK, TRADING UNDER THE NAME WYOMING BROOM COMPANY, OF WILKES-BARRE, PENNSYLVANIA.

BROOM.

1,207,457.

Specification of Letters Patent.

Patented Dec. 5, 1916.

Application filed April 6, 1916. Serial No. 89,449.

To all whom it may concern:

Be it known that I, FRANK M. WILLIAMS, a citizen of the United States, residing at Wilkes-Barre, in the county of Luzerne and 5 State of Pennsylvania, have invented certain new and useful Improvements in Brooms; and I do declare the following to be a full, clear, and exact description of the invention, such as will enable others skilled 10 in the art to which it appertains to make and use the same.

This invention relates to brooms and more particularly to those having protective metal caps.

15 The principal object of the invention is to so construct a broom that the straws, fibers, or other material from which the brush thereof is formed are securely held in engagement with the handle and liability of 20 the individual fibers becoming accidentally detached is effectively obviated.

With these and other objects in view, the invention consists of certain novel features of construction, and the combination and arrangement of parts as will be hereinafter 25 more fully described and claimed.

In the accompanying drawings: Figure 1 represents a perspective view showing the stock bundled and inserted within the securing ring with the handle in position therein prior to the compression of the ring; Fig. 2 is a similar view showing the parts after having been compressed; Fig. 3 is a vertical central section through the broom head after the 30 fibers have been folded forward and before the cap has been placed thereon; Fig. 4 is a central vertical section taken on the line 4—4 of Fig. 5; Fig. 5 is a similar view taken on the line 5—5 of Fig. 4 in a plane at right 35 angles to Fig. 5; Fig. 6 is a transverse section taken on the line 6—6 of Fig. 4; Fig. 7 is a side elevation of the broom complete with the handle broken off; and, Fig. 8 is a detail perspective view of one of the cap 40 fastening elements.

In constructing a broom in accordance with this invention a sufficient quantity of broom straw, splints of suitable tough timber or any other fiber of which it is desired 45 to construct the brush of the broom is bundled together as indicated in Fig. 1 of the drawings and a heavy metal ring 1 is placed over one end thereof, the ring being shown composed of heavy wire, a handle H 50 of ordinary construction having been ar-

ranged centrally within the bundle of fibers. It is to be understood that the ring is completely filled with the fibers 3 having the handle embedded therein and after they have been so placed the ring-encircled bundle is compressed laterally by any suitable means and at the same time securing nails or staples 2 which are arranged at diametrically opposite points and straddle the wire ring 1 are forced into the handle, sufficient 60 pressure being applied to change the conformation of the ring 1 into oval shape and the bundle is flattened until it becomes substantially oval in cross-section. This flattening of the ring 1 with the fibers contained 65 therein reduces the area thereof so that the fibers are compressed into such close engagement with each other and with the handle that it is practically impossible for them to work loose or become accidentally detached 70 even after they have become thoroughly dried, it being understood that these fibers are moistened before they are arranged within the ring 1 such as is customary in making 75 brooms of this character.

After the straws or fibers 3 have been secured as above described within the ring 1 they are turned over into the position shown in Figs. 3 and 4 and with the ring-encircled end thereof extending forwardly into the 80 body of the broom. After these fibers have been so turned a metal cap 4 is placed over the turned end thereof and is designed for protecting the upper end or head of the broom and to assist in confining and holding 85 the fibers in operative position so bracing them that they will retain their shape and position even under great strain.

The hood or cap 4 is preferably constructed of any suitable sheet metal and consists of a solid piece of metal pressed out by properly constructed dies without the formation of any joints or seams therein, thereby producing a very strong and durable 90 cap and one having a smooth surface to 100 avoid any possibility of adjacent objects being engaged therewith. This cap 4 has a reduced neck 5 shaped to conform to the handle H and is secured thereto by suitable fastening elements 6 which pass through 105 openings in the neck 5 and enter the handle H as indicated in Fig. 1. This metal cover or cap 4 is securely fastened to the brush by means of suitable fasteners 7 shown in detail in Fig. 8. These fasteners 7, any de- 110

sired number of which may be employed, are preferably constructed of steel or any other metal of sufficient stiffness or rigidity to adapt them to be driven through both 5 side walls of the metal cover and through the fibers forming the brush head. These fasteners 7 before being inserted are in the form shown in Fig. 8 and have a laterally extending arm 8 with an inwardly and forwardly extending penetrating prong 9 arranged parallel with the body portion thereof and which is designed to be driven through one side wall of the hood or cap 4, the body of the fastener also being passed 10 through the cap at this side. After the fastener 7 has been driven through both side walls of the cap and the straw disposed between said walls, the pointed end 10 is engaged by a suitable tool and bent inwardly and passed through the cap wall at 15 the side of the broom opposite that through which prong 9 is passed, as shown in Fig. 6. It will thus be observed that each fastening has a double bearing on both sides of the 20 metal cap or hood 4 and thus securely connects the opposed walls of said cap and firmly clamps the fibers forming the brush between them. These fasteners 7 do not penetrate the handle H but are arranged on 25 opposite sides thereof and the lower or inner end of the handle is secured to the cap by oppositely disposed nails 11 as shown in 30 Figs. 5 and 6.

From the above description it will be obvious 35 that a broom constructed as herein described may be quickly formed and when

completed the straws or fibers thereof will be so firmly held as to render it practically impossible to pull them out.

I claim as my invention:

A broom comprising a handle, a bunch of brush material surrounding one end of said handle and one end thereof extended in the same direction as said handle end, an oval shaped wire retaining band encircling said material and handle, staples straddling said band and engaged with said handle at diametrically opposite points, said bunched material being bent outwardly and forwardly over and inclosing said band and the ends 45 of the material and of the handle mounted in said band, whereby both ends of the bunched material extend in the same direction, a protective hood incasing the handle connected end of the brush and having a 50 neck fitting the handle at the rear of the brush, fasteners passing through said neck and engaging said handle, fasteners extended through both side walls of said hood and the brush material with the ends of said fasteners extended inwardly through said 55 hood walls at points spaced from the entrance of the body portion of the fasteners, and headed fasteners extending through opposite sides of said hood into said handle. 60

In testimony whereof I have hereunto set my hand in presence of two subscribing witnesses.

FRANK M. WILLIAMS.
